FRINGE.

No. 18,366.

Patented June 5, 1888.

UNITED STATES PATENT OFFICE.

GEORGE S. HENSEL, LOUIS D. VALETTON, AND FRANK E. COOK, OF PHILADELPHIA, PENNSYLVANIA, ASSIGNORS TO THE HENSEL, COLLADAY COMPANY, OF SAME PLACE.

DESIGN FOR FRINGE.

SPECIFICATION forming part of Design No. 18,366, dated June 5, 1888.

Application filed April 28, 1888. Serial No. 279,209. Term of patent 7 years.

To all whom it may concern:

Be it known that we, GEORGE S. HENSEL, LOUIS D. VALETTON, and FRANK E. COOK, citizens of the United States, residing in the city and county of Philadelphia, State of Pennsylvania, have invented and produced a new and original Design for Fringes, of which the following is a specification, reference being had to the accompanying photograph, forming part thereof.

The leading features of our design for fringe are, first, scroll-shaped figures with dots on the head thereof, and, next, a double row of festoons at the base of said head.

In the photograph, A represents the head of the fringe, and B the pendants thereof. On the head are scroll-shaped figures 1, which are joined by scallops 2. At the junction of adjacent scallops are dots 3. At the base of the

head is a double row of festoons, 4. At the top of the pendants are knots 5.

We claim--

1. The design for a fringe herein shown and described, consisting of a head having thereon the scroll-shaped figures 1, the scallops 2, and dots 3, and at its base a double row of festoons, 4, and pendants B, substantially as described.

2. In a design for a fringe, a head portion having thereon scroll shaped figures with scallops and dots, substantially as shown and described.
